United States Patent Office.

HENRY D. MUSSELMAN, OF LANCASTER, PENNSYLVANIA.

Design No. 2,549, dated January 15, 1867.

DESIGN FOR THE BOTTOM OF A FRYING-PAN.

The Schedule referred to in these Letters Patent and making part of the same.

TO ALL WHOM IT MAY CONCERN:

Be it known that I, HENRY D. MUSSELMAN, of the city of Lancaster, in the State of Pennsylvania, have originated and designed a new pattern for Frying-Pans, of which the accompanying drawings, making part of this specification, show a perspective view by Figure 1; Figure 2 being a birdseye view or plan of the same, and of which the following is a full, clear, and exact description, reference being had to the drawings aforesaid.

The pan is cast from the pattern of my design in the ordinary manner. A shows the handle, B the spout of the pan C. Around the bottom, on the inside, is a groove, E, and a central groove, D, from the handle. At right angles to this central groove the bottom is fluted or covered with a series of parallel grooves or channels, as shown. These channels are deep and rounded, producing narrow and smooth ridges. These parallel grooves all open, both into the central cross-channel D and the groove E, along the circumference of the bottom on the inside.

What I claim as my invention, and desire to secure by Letters Patent, is—
The design and configuration of the pan, as shown and described herein.

HENRY D. MUSSELMAN.

Witnesses:

WM. B. WILEY,
JACOB STAUFFER.
